Fig. 2.

Fig- 3-

A technical drawing of a mechanical assembly, likely a valve or actuator, shown in cross-section. The drawing is labeled with numerous numbers, likely referring to a parts list or patent claims. Key labeled parts include:

- 66: A top cap or cover.
- 21: A small part near the top.
- 42: A part on the right side.
- 67: A part on the left side.
- 64: A part below 67.
- 62: A part below 64.
- 45: A part on the right side.
- 47: A part on the far right.
- 49: A part below 47.
- 51: A part on the far left.
- 48: A part below 51.
- 50: A part below 48.
- 52: A part below 50.
- 44, 53: A pair of parts, one above the other.
- 43: A part on the far left.
- 64: A part at the bottom left.
- 43: A part at the bottom right.

UNITED STATES PATENT OFFICE.

STANLEY M. RATLIFF, OF NORWOOD, OHIO, ASSIGNOR TO THE AMERICAN TOOL WORKS COMPANY, OF CINCINNATI, OHIO, A CORPORATION OF OHIO.

TRAVELING DRILLING MACHINE.

Application filed August 18, 1926. Serial No. 130,055.

My invention relates to drilling machines arranged to be moved bodily with relation to the work, the work being at times long castings or other structures in which holes 5 are to be drilled at distances from each other outside the range of adjustment of a stationarily positioned drilling machine, the work being heavy or cumbersome, so that it has been found more economical in practice to adjust the machine than to adjust the work.

It is the object of my invention to provide novel means for controlling the location of the drilling machine; further, to place the controlling means for travel on the drilling machine, within easy reach of the operator from his usual operating positions; further, to arrange said controlling means so that the same will move laterally with 20 the drill-slide upon adjustment of the drill-slide; and, further, to locate the controlling means in such positions with relation to the drill-slide, and the usual adjusting and operating parts thereon to be handled by the 25 operator, that the operator instinctively and automatically finds said controlling means from his usual operating positions when it is desired to change the position of the drilling machine with relation to the work.

The invention will be further readily understood from the following description and claims, and from the drawings; in which latter:—

Fig. 1 is a perspective view of my improved device partly broken away.

Fig. 2 is a horizontal plan section of the same, taken on the line 2—2 of Fig. 1.

Fig. 3 is a horizontal section of the same taken in the plane of the line 3—3 of Fig. 1.

Fig. 4 is a vertical cross-section, taken in the plane of the line 4—4 of Fig. 3.

Fig. 5 is a vertical section of a detail of the same, taken on the line 5—5 of Fig. 1.

Fig. 6 is a cross-section of the same taken in the plane of the line 6—6 of Fig. 5.

Fig. 7 is a diagrammatic view of the electric circuits of my improved device.

Fig. 8 is an end view, partly in section on the line 8—8 of Fig. 9, and partly broken away, showing a modification of the driving means of my improved device.

Fig. 9 is a side elevation of the same, partly broken away.

Fig. 10 is a longitudinal section, taken on the line 10—10 of Fig. 8.

Fig. 11 is a cross-section of a detail of the same, taken on the line 11—11 of Fig. 9. The drilling machine may be any usual drilling machine, and is exemplified as including a base 21 from which a post 22 extends upwardly. The post is usually integral with the base, rotatable column 23 is rotatable and held parallel with the axis of the post in usual manner, there being suitable bearings between the rotatable column and the post.

A clamp is arranged to clamp the rotatable column in desired radial positions with relation to the base, exemplified a clamp-bearing 24 about a lower journal part of the post, operated in suitable manner, manually or by power.

A drill-arm 25 has a bearing 26 about the column, and is adjustable to elevation thereon, as by means of a screw-rod 27 extending lengthwise to the column and a suitable coacting nut held endwise on the arm. Suitable relative rotation is caused between the screw-rod on the nut by suitable and usual means for raising and lowering the drill-arm. The drill-arm is arranged to be clamped to the column in desired elevational positions by suitable clamping means 28.

The drill-arm is exemplified as rotatable with the column for desired radial positioning of the drill-arm with relation to the base.

A drill-slide 31 is adjustable laterally on the drill-arm, as on guides 32, 33, the lateral adjustments being effected by suitable means, which are instanced as including a rack 34 extending lengthwise of the drill-arm, a pinion suitably mounted on the drill-slide, meshing therewith and operated by suitable gearing between the pinion and 95 suitable handles 35, 36, on a cross-shaft 37, journaled in the slide.

The slide has a drill-spindle 38 journaled and feedable axially therein. The spindle is arranged to have a suitable drill 39 fixed thereto in usual manner for coacting with the work, which may be of indefinite length and parallel with the track.

This work is usually cumbersome and difficult to handle and is at times long and very heavy, so that it is desirable to move the

drilling machine proper with relation to the work rather than to adjust the work into different positions with relation to the drilling machine.

The means for accomplishing this are exemplified as a carriage 41, on which the base 21 of the drilling machine is fixed, as by means of bolts 42.

The carriage is arranged to be moved along a track, which may be of indefinite length, exemplified at 45, which is rigidly secured to the foundation supporting the same to prevent tilting.

The track is shown as a sub-base, in Figs. 1 to 4 inclusive. Guides 46, 47, extend lengthwise of the sub-base, and coact with guide-ways 48, 49, on the carriage. The track supports the weight of the carriage and of the drilling machine mounted thereon.

The securing means for securing the sub-base to the foundation, are exemplified as anchor bolts 43 and nuts 44.

Side flanges 50 depend from the carriage and are rigid therewith, and coact with end faces 51 on the track, for maintaining alignment between the carriage and the track. Lower inwardly extending flanges 52, rigid with the carriage, coact with under guide-faces 53 on the track, at the respective sides of the track, for preventing tilting of the carriage and machine carried thereby. Suitable adjustments may be provided for the flanges. The flanges are shown as forming protecting aprons for the guides.

The means for moving the carriage lengthwise of the track are exemplified in Figs. 1 to 4 inclusive, as comprising a rack 61 extending lengthwise of and fixed to the sub-base or track, and a pinion 62 on the carriage. The pinion is fixed to a shaft 63 journaled in a bearing 64 in a gear box 65 fixed to the carriage. The shaft 63 has a worm-wheel 66 fixed thereto. A worm 67 meshes with the worm-wheel and is fixed to a shaft 68 journaled in bearings 69 of the gear-box 65. The worm-shaft 68 has a gear 70 fixed thereto, which is meshed by a pinion 71 fixed to a shaft 72, journaled in a bearing 73 on the gear-box, and in a bearing 74 on an upright 75 extending from the carriage. The shaft 72 extends through the base 21, and is located in holes 76 therein, the walls of which may form bearings if desired.

A motor 81, shown as an electric motor, is fixed to the carriage, the rotor-shaft 82 of said electric motor having suitable drive connection, instanced at 83, with the shaft 72.

The motor is instanced as an electric motor, and the power-supplying means are instanced as a suitable electric circuit for said motor, and the power controlling means are instanced as a partial circuit leading to the drill-slide and having an electric translating device movable with the drill-slide,

although it is obvious that other motive power, power supplying means, power controlling means and control operating means may be employed, without departing from the spirit of my invention within the scope of the appended claims.

The electric motor is instanced as a reversible motor for rotating the shaft 72 in reverse directions, as desired, for moving the carriage in one direction, or in the opposite direction, selectively, for placing the drilling machine at any desired point along the track for cooperation at any desired point with the work.

The electric motor 81 is instanced in main electric circuits including a suitable source of electric energy, as the generator in a suitable power circuit.

The respective main electric circuits include operated elements 85, 86, and 87, 88, for closing said respective main electric circuits, which operated elements are respectively controlled by magnetizing elements 89, 90, forming magnetic switches 91, 92, the armatures 93, 94, of which are shown supporting the electro-conductive parts 85, 86, and 87, 88, of said switches, although the armatures may form such electro-conductive parts.

The main electric circuits may comprise feed wires 101, 102, connecting with any suitable source of electric power, as the generator of a power circuit. These wires are electrically connected with the electro-conductive operated elements 87, 88, arranged to be drawn against the contacts 103, 104, in wires 105, 106, leading to the motor 81.

Wires 107, 108, lead from the wires 101, 102, and are connected with the electro-conductive operated elements 85, 86, which are arranged to make contact with the electric contacts 109, 110. Wires 111, 112, connect these contacts respectively with the wires 106, 105, for rotating the motor in the opposite directions.

The magnetizing elements are preferably in control circuits, in which these are manually operated electric translating devices, shown as switches 115, 116.

The respective control circuits are shown as partial circuits, the respective ends of which are connected with the respective co-operating main circuits at opposite sides of the respective magnetic switches for the respective main circuits.

The control circuits are shown as by-pass circuits or partial circuits which include electric conductors 117, 118, and a common electric conductor 119. The common electric conductor 119 is instanced as connecting with the main electric conductor 101. An electric resistance 120 is preferably in this conductor. The partial circuits carry considerably less electric potential than the main circuits, principally for safety reasons.

The electric conductor 117 is shown as including the magnet 89 and as connecting with the main line 102. The electric conductor 118 is shown as including the magnet 90 and as connecting with the main line 102.

One of the main circuits may be instanced for rotating the motor in one direction, the magnetic switch 91 and the manually operated switch 115 controlling said main circuit, and the other main circuit may be instanced for rotating said motor in the opposite direction, and is controlled by the corresponding magnetic switch 92 and the manually operated switch 116.

It is of course obvious that other electric circuits and connections may be employed, depending on the character of electric motor and electro-motive force employed.

The magnetic switches are instanced as contained in a magnetic switch-box 124 mounted on the carriage. The manual control means for the motor are mounted at the operator's position, being supported by the drill-arm, and are instanced as movable with the drill-slide. For this purpose the manual operating switches 115, 116, are shown mounted in a switch-box 125, secured to the drill-slide, and movable therewith. The manual operating switches are instanced as in normally open circuits, held normally open by means of the springs 126, 127.

The respective switches are arranged to be closed by means of push-buttons, for moving the carriage respectively forward or back, as long as either of the push-buttons is pushed inwardly, the motor 81 stopping as soon as the pressure is released from the button.

Means are further provided in the motor control means, for compensating for the various lateral positions to which the drill-slide may be adjusted and the various elevations to which the drill-arm may be adjusted, comprising, for instance, automatic take-up means 131, exemplified as at the carriage, and as mounted on the clamp bearing 24 of the column, so as to move with the column and the drill-arm into the various radial positions of the same.

The take-up means may comprise a spool 132, provided with electro-conductive contact rings 133, 134, 135, with which the electric conductors 117, 118, 119 of the partial circuits are connected by binding posts 136, 137, 138. The spool is preferably of insulating material.

The spool rotates about a stud-shaft 140, shown fixed to the clamp bearing 24 at the lower end of the rotatable column. The spool is held endwise to the stud-shaft by a washer 141 and a nut 142 received about the threaded reduced end of the stud-shaft.

A spiral spring 143 is received about the stud-shaft, one end thereof being received in a hole in the column, and the other end

thereof being received in a hole in the spool. Electric contacts 144, 145, 146, urged by springs 147, coact with the rings on the spool, and are received in blocks 148, 149, 150, and have binding posts 151, 152, 153, to which the continuations of the electric conductors 117, 118, 119, are secured.

The portion of the electric conductors 117, 118, 119, between said take-up means and the switches 115, 116, shown located on the drill-slide are preferably located in a cable 154.

The spring 143 automatically takes up the slack which may be in the cable between the drill-slide and the take-up means. The cable may be directionally guided over a sheave 155, rotatable about a stud 156, fixed to the bearing 26 of the drill-arm about the column.

The continuations of the electric conductors 117, 118, 119, are secured to the last-named binding posts and extend to the magnetic switch-box 124, being preferably located in a cable 157, which is of sufficient length and arranged loopwise, so as to permit the swinging of the radial drill-arm into all desired radial positions.

The electric conductors 117, 118, 119, and the cables 154, 157, are preferably flexible, so as to conveniently permit said movements.

When the operator adjusts the drill-slide laterally on the drill-arm, and when he adjusts the drill-arm to elevation on the column, the take-up means 131 take up any slack there may be in the cable, or permits paying out of the cable, according to the demands upon the same made by the adjustments. These parts also move with the carriage upon adjustment of the carriage lengthwise of the track.

The magnetic switches are preferably stationarily positioned on the carriage with relation to the motor shaft, so that movements of the main electric conductors may be reduced to the minimum. The partial circuits are the circuits which are led to the drill-slide, and controlled therefrom.

By means of my improved device, the operator is able to cause travel of the drilling machine, from his position in performing the drilling operations upon the work, which position is indicated at *a* in front of the drill-arm and at the right of the drill-slide, when facing the drill-arm, enabling him to adjust the position of the drilling machine with relation to the work with great accuracy. Control circuits of comparatively small electric potentiality are provided, leading to the drill-arm and the operator's position, the manual operating part thereof being shiftable with the adjustments of the drill-slide and of the drill-arm for controlling the main electric circuits movable with the carriage.

The carriage remains in adjusted position due to the locking engagement between the worm-wheel and the worm, and the friction

between the guides of the carriage and the track.

My invention is simple, and provides for extreme convenience, accuracy and safety in manipulation.

I have in Figs. 8 to 11 inclusive shown a modification of my improved device, in which the track is instanced as comprising rails 161, on which wheels 162, 163, respectively fixed to axles 164, 165, are arranged to travel. The rails are rigidly fixed to the foundation supporting the same to prevent tilting of the supported parts, as by means of anchor-bolts 158, and nuts 160.

The axle 164, is journaled as in bearings 166 on the carriage, and the axle 165 is journaled in bearings 167 on the carriage. These bearings are located in depending flanges 168, depending integrally from the platform 169 of the carriage. The depending flanges 168 are provided with inwardly extending shoes 170 received under and slideable lengthwise of the heads 171 of the rails. The wheels are provided with flanges 172 positioned along the inner faces of said heads. Lateral positioning of the carriage is thus assured, and maintaining the parallelism of the carriage with the track is assured.

The inwardly extending shoes 170 may be adjustable as by means of set-bolts 175 threaded in lugs 176 of the flanges 168 and bearing against the shoes. Clamp-bolts 177 are received through slots 178 in the shoes 170 and holes 179 in the flanges 168 and have nuts 180 received thereover for clamping the shoes to the carriage. The flanges 168 form protecting aprons for the track and wheels.

In this modification, the shaft is instanced as provided with a pinion 185, meshing with a gear 186, fixed to a worm-shaft 187, journaled in bearings 188 on the carriage. The worm-shaft has a worm 189 fixed thereon, which meshes with a worm-gear 190, fixed to the axle 164. Bearings 191, are shown at the respective sides of said worm-wheel, about the axle 164, and are located on hangers 192, depending integrally from the carriage.

Having thus fully described my invention, what I claim as new, and desire to secure by Letters Patent, is:

1. In a traveling drilling machine, the combination of a track, a carriage movable therealong, a base fixed to said carriage, a post extending rigidly upwardly from said base, a rotatable column about said post above said base, a drill-arm adjustable to

elevation on said column and arranged to be adjusted to radial positions with relation to said carriage, a drill-slide slideable laterally on said drill-arm toward and from said column, means at said carriage for travel of said carriage on said track, said last-named means including a shaft extending through said base below said rotatable column, a motor supported by said carriage connecting with one end of said shaft at one side of said base for driving said shaft, and power connecting means at the opposite side of said base connecting the other end of said shaft with said track, power controlling means for said motor, and control means for the latter on said drill-arm.

2. In a traveling drilling machine, the combination of a track, a carriage movable therealong, a base fixed to said carriage, a post extending rigidly upwardly from said base, a rotatable column about said post above said base, a drill-arm on said column, a drill-slide slideable laterally on said drill-arm toward and from said column, a carriage moving shaft extending through said base below said rotatable column, a motor supported by said carriage at one side of said base, power connecting means at the opposite side of said base, said power connecting means connecting with said track, said power connecting means and said motor connecting with the respective ends of said shaft at the respective sides of said base, and power controlling means for said motor.

3. In a traveling drilling machine, the combination of a track, a carriage movable therealong, a base fixed to said carriage, a post extending rigidly upwardly from said base, a rotatable column about said post above said base, a drill-arm adjustable to elevation on said column and arranged to be adjusted to radial positions about said post, a drill-slide slideable laterally on said drill-arm toward and from said column, a shaft extending through said base below said rotatable column, a motor at one side of said base connecting with one end of said shaft, a worm and worm-wheel at the opposite side of said base connecting with the other end of said shaft, said worm and worm-wheel having operative connection with said track for moving said carriage lengthwise of said track.

In testimony whereof, I have hereunto signed my name.

STANLEY M. RATLIFF.
